Williamson & Merchant

UNITED STATES PATENT OFFICE.

JAMES A. ALLARDYCE, OF MINNEAPOLIS, MINNESOTA.

AEROPLANE.

1,383,509.

Specification of Letters Patent.

Patented July 5, 1921.

Application filed March 8, 1920. Serial No. 364,143.

To all whom it may concern:

Be it known that I, JAMES A. ALLARDYCE, a citizen of the United States, residing at Minneapolis, in the county of Hennepin and 5 State of Minnesota, have invented certain new and useful Improvements in Aeroplanes; and I do hereby declare the following to be a full, clear, and exact description of the invention, such as will enable others 10 skilled in the art to which it appertains to make and use the same.

My invention relates to flying machines of the type known as aeroplanes, and has for its object to increase the stability thereof 15 and to make it practically impossible to capsize the same. Otherwise stated, the invention has for its object particularly to make aeroplanes safer for ordinary travel, either for pleasure or commercial purposes, 20 but does not attempt to provide an aeroplane capable of use for trick purposes, fancy flying or speed.

The salient feature of the invention consists in using a gas tank formed with air 25 stream lines, or of the general form commonly designated as "cigar shape," in placing the gas tank above the center of gravity of the aeroplane and extending the same parallel to the fuselage. It is not intended 30 that this gas tank should be of such size as to carry the entire weight of the aeroplane, but it will assist in supporting the said weight in the air and afford a partial support from which the greater part of the 35 weight of the aeroplane is suspended in such a manner that it would be impossible, or at least very difficult, under any circumstances, to capsize the aeroplane.

The gas tank should be provided with a 40 plurality of gas-tight compartments preferably spaced longitudinally thereof. This gas tank, of course, increases the buoyancy of the aeroplane so that it will more quickly rise under the advance movement of the 45 plane and may be caused to alight with a less shock when the plane is moving very slowly in landing.

To the above end, the invention consists of the novel devices and combinations of devices hereinafter described and defined in 50 the claims.

In the accompanying drawings, which 55 illustrate the invention, like characters indicate like parts throughout the several

Referrig to the drawings:—

Figure 1 is a plan view of an aeroplane having the invention incorporated therein; Fig. 2 is a front elevation of the same; Fig. 3 is a right side elevation; and Fig. 4 is a fragmentary longitudinal section taken centrally through the gas tank.

The invention, as shown in the drawings, is incorporated in a flying machine of the biplane type, and of the parts thereof, it is 60 important to note the fuselage 5 and planes 6.

Said invention comprises a gas tank 7 made of balloon fabric, or other suitable material, and has stream air lines which closely follow the general shape of the fuselage 5. The gas tank 7 is located above the center of gravity of the aeroplane, and as shown, is placed between the planes 6 above the fuselage 5 and substantially parallel thereto. Cables 8 are provided for anchoring the gas tank 7 to the fuselage 5.

By reference to Fig. 4, it will be noted that the gas tank 7 is provided with a plurality of transverse partitions 9, which divide the gas tank into a multiplicity of longitudinally spaced compartments 10, each of which is provided with a valve 11 to which may be attached a gas-charging tube.

While the invention is shown as incorporated in a machine of the biplane type, it 85 is, of course, understood that the same may be used on various different types of machines, and in some instances, it might be desirable to use more than one gas tank.

While this invention is especially directed 90 to an aeroplane in which the gas tank will carry only part of the weight of the machine, nevertheless, within the broad scope of this invention, it might be increased in size so as carry the entire weight of the 95 machine and one or more passengers. In fact, I believe it is broadly new in my invention to connect the gas tank, the fuselage and supporting planes rigidly or in such a manner that they all move together or as a 100 single unit.

What I claim is:

1. The combination with a biplane of the ordinary type comprising a fuselage and planes, of a cigar shaped tank containing 105 a buoyant gas, said tank having pointed ends and having its longitudinal axis parallel to the longitudinal axis of the fuselage, said tank being disposed immediately under the top plane and being firmly secured in 110

position to said plane and fuselage and being of a length substantially the same as the fuselage.

2. The combination with a biplane comprising the usual fuselage, and planes, of an elongated cigar-shaped tank having transverse portions forming separate chambers therein, all of which are inflated with a buoyant gas, said tank having pointed ends 10 and having its longitudinal axis parallel to

the longitudinal axis of the fuselage, and being disposed immediately under the top plane, means for firmly securing said tank to the plane and fuselage, said tank having a diameter not greater than the maximum 15 width of the fuselage and being of substantially the same length as said fuselage.

In testimony whereof I affix my signature.

JAMES A. ALLARDYCE.
